BAG LOCK

Filed March 24, 1925

UNITED STATES PATENT OFFICE.

FRANK T. STUART, OF MAPLEWOOD, NEW JERSEY, ASSIGNOR TO THE R. NEUMANN HARDWARE CO., A CORPORATION OF NEW JERSEY.

BAG LOCK.

Application filed March 24, 1925. Serial No. 17,878.

This invention relates, generally, to locks; and, the present invention has reference, more particularly, to improvements in bag-locks employed with the usual complements of frame-members or sections of a bag-frame, with a view of providing, primarily, a lock-construction the mechanism of which is to be operated by a key, but in which the push-member of the lock is provided with 5 means which permits of the mechanism to be operated only by a certain key.

In other words, while the construction and the arrangement of the parts of the mechanism of the lock is the same in all locks, 10 the means within the push-member which permits the turning of the key, varies with the several locks, so that different keys are necessary with different locks.

This invention, therefore, has for its principal object to provide the push-members of the usual bag-locks, with simply constructed means within the push-member of the lock, which will allow of a certain key turning within said member, but will remain inoperative when another key is inserted.

Another object of the present invention is to provide with the casing of a bag-lock, and its mechanism therein, a push-member made of cast or similar metal, instead of being formed in sheet-metal, as heretofore, so as to produce a push-member of greater strength, and one in which there are no rough or sharp edges due to the imperfect structure of the member, as is so often the case, where the push-member is made from sheet-metal.

Other objects of the present invention not at this time more particularly enumerated will be clearly understood from the following detailed description of the said invention.

With the various objects in view, the present invention, consists in the novel bag-lock hereinafter set forth; and, the said invention consists, furthermore, in the novel arrangements and combinations of the various devices and parts, as well as in the details of the construction of the said parts, all of which will be more fully described in the following specification, and then finally embodied in the clauses of the claims, which are appended to and which form an essential part of the said specification.

The invention is illustrated in the accompanying drawings, in which:—

Figure 1 is a view of a fragmentary portion of a bag-frame section, looking toward the interior of said section, and showing in elevation, in connection with said frame-section, a bag-lock made according to and embodying the principles of the present invention.

Figure 2 is a longitudinal vertical sectional representation of said bag-frame section and an elevation of the lock attached thereto, looking at the lock from the opposite side of that shown in said Figure 1; Figure 3 is a longitudinal vertical section of the lock, shown detached from the frame-section; and Figure 4 is a horizontal section, taken on line 4—4 in said Figure 3, looking in the direction of the arrow α .

Figures 5, 6 and 7 are perspective views of three push-members to be used with the lock-mechanism, shown provided with variously located key-stops, and the corresponding and variously notched keys adapted to be used with the said push-members.

Figure 8 is an end view of one of said push-members; Figure 9 is a longitudinal vertical section of the same, said section being taken on line 9—9 in said Figure 8; and Figure 10 is a perspective view of the key-receiving barrel used with the push-member.

Similar characters of reference are employed in all of the said above described views, to indicate corresponding parts.

Referring now to the said drawings, the reference-character 1 indicates a portion of any usual bag-frame section to which the lock is attached in a manner, substantially as indicated in Figures 1 and 2 of the drawings.

The lock comprises any usual casing, the one here shown consisting of the longitudinally extending side-face 2, the base 3, and the end-members 4, thus providing a casing which is open at one side, but which open side is placed against the vertical flange-member 5 of the frame-section 1, as will be evident from an inspection of Figure 1 of the drawings. This lock-casing, thus provided, is formed in its side-face 2 with suitably disposed hasp-lug receiving openings 6, and connected with and extending in an

upward direction from each end-member 4 is a fastening ear or lug 7. These ears or lugs 7 are inserted through correspondingly located slits or openings 9 of a top-plate 8, said plate being formed along one of its longitudinally extending marginal edges with the usual right-angled flange 10, and connected with and extending from the ends of said top-plate are suitably formed fastening ears or lugs 11 which are inserted in and passed through the usual slits or openings in the frame-section 1; and are then passed through correspondingly located slits or openings 13, indicated in dotted outline, in a plate 12 of the usual casing 14 located upon the upper and outer face of the frame-section 1, as indicated in Figure 2 of the drawings.

Within the said lock-casing is the usual key-operated locking-mechanism comprising the sliding bolt or latch-plate 15, and the push-lug-operated bridge-member 16 which is provided with upwardly extending lugs 17 adapted to be brought into retaining engagement with the usual hasp-lugs 18, as indicated in said Figure 2, when said lugs 18 enter the openings 6. The said bridge-member 16 is mounted upon the posts 19, secured at their lower ends to a plate 20 and to the said base-plate 3 of the lock-casing substantially as shown in Figure 3 of the drawings. Encircling said posts 19, between said bridge-member 16 and the said plate 20 are coiled springs 21, the purpose of which is self-evident. In connection with said bridge-member is the push-member of the bag-lock, the said push-member being compressible when the bolt or latch-plate 15 is in the position indicated in Figure 3 of the drawings, for the withdrawal of the lugs 17 from their holding engagement with the hasp-lugs 18, as will be evident.

The above-mentioned push-member consists, essentially, of a main cast-metal body-member 22, preferably of rectangular configuration, as indicated in the several figures of the drawings, the said body-member at its lower part being provided with an off-set portion 23, usually formed with a cut-out portion or recess, as 24. Extending from said off-set portion 23 are posts 25, the end-portions 26 of which are fitted into suitable perforations 27 in the bridge-member 16, and are riveted over or upset against the lower face of the bridge-member for positively securing the push-member upon said bridge-member. The said body-member 22 is also formed with a central and vertically disposed central bore, as 28, the upper open portion of which is marginally bounded by an annular rib 29, a portion of which is cut away or slotted, as at 30. Also suitably maintained in position upon the bridge-member 16, by means of an extension 32, rotatably disposed in an opening 33 in the

bridge-member, is a key-receiving barrel 31. This barrel, as will be seen from Figure 10 of the drawings, is made with an annular rib 34, an enlargement 35, and with an annular off-set 36, all arranged so as to permit of a 70 rotatable arrangement and the operative retention of the key-barrel within barrel-receiving bore of the push-member, as will be evident from an inspection of Figure 3 of the drawings.

The said key-barrel is furthermore longitudinally slotted, as at 37, the slot passing through the body of said barrel, and also through the parts 36, 35, 34 and 32 of the same, as indicated in said Figure 10. Inserted and secured in a hole 38, extending laterally through one side of the body-member 22 of the push-member is a controlling means, in the form of stop-pin 39, the inner end-portion of which extends into and terminates in the annular space 40 formed by the wall of the bore 28 and the respective surface-portions of the parts 31, 34 and 35 of the key-barrel, substantially as shown in said Figure 3 of the drawings.

The key used with the said key-barrel is indicated by the reference-character 41 and is of the flat style to permit of its insertion in the slot 37, and the parts of the key for actuating the lock-mechanism are of the usual shapes. In order, however, to enable the key to be used with the push-member shown in Figures 3 and 5 of the drawings, the key 41 is provided in its edge 42 with a cut-away or recessed portion 43, corresponding to the location of the stop-pin 39, so as to permit the turning of the key past the inner end-portion of the stop-pin terminating and located in the space 40, during the locking and unlocking operations of the key, as will be fully understood from an inspection of said Figures 3 and 5.

Referring now to Figures 6 and 7 of the drawings, it will be seen, that the stop-pins 39 may be variously located in the body of the push-member, and that different keys, as 44 and 45, supplied with correspondingly located recess 46 and 47, may be provided, so that the key 41, can only be used with the push-member shown in Figure 5, the key 44 only with the push-member shown in Figure 6, and the key 45 only with the push-member shown in Figure 7.

Of course, it will be understood, that other combinations of the pins 39 and the recessed portions of the keys may be made, and that if desired, the push-members may be provided with a plurality of pins 39, the keys being provided with a corresponding number of such variously located recesses in the edges of the respective keys.

As has been previously stated the push-member is made from cast-metal, or a solid block of metal, with the bore thereof being produced by drilling, may be used, the pur-

pose being to do away with the usual form of hollow sheet-metal push-member which is objectionable in that it lacks strength, is unfinished in appearance, and is often left with 5 objectionable sharp marginal edges, which with constant use open up, and thereby leave unsightly seams.

Of course, I am aware, that other changes may be made in the general arrangements 10 and combinations of the various devices and parts, as well as in the details of the construction of the said parts, without departing from the scope of the present invention as set forth in the foregoing specification, and 15 as defined in the clauses of the claim which are appended thereto. Hence, I do not limit my present invention to the exact arrangements and combinations of the various devices and parts as described in the said specification, nor do I confine myself to the exact details of the construction of the said 20 parts, as illustrated in the accompanying drawings.

I claim:—

25 1. A bag-lock comprising a casing, a de-
pressible hasp-engaging means within said
casing, an upwardly and exteriorly project-
ing push-member secured to said hasp-en-
gaging means, key-actuated means movable
30 to obstruct or release said hasp-engaging
means for operation, said push-member hav-
ing a vertical bore, a key-receiving barrel
rotatable in said bore having a longitudinal
key-slot open along one side thereof, said
35 barrel having at its lower extremity a re-

duced axial extension journaled in said hasp-
engaging means, said barrel having inter-
mediate its ends a reduced portion providing
an annular space between the same and the
walls of said bore and a stop-pin fixed in 40
said push-member to project into said annular
space in predetermined position to match with a selectively located clearance
notch of a proper key inserted in said barrel.

2. A bag-lock comprising a casing adapted 45
to be attached to a bag-frame, a lock-mech-
anism within said casing, a spring-supported
hasp-engaging bridge-member cooperating
with said lock-mechanism, a push-member
for actuating said bridge-member, said push- 50
member having an axial cylindrical bore, a
key-receiving barrel rotatable in said bore
and provided with a longitudinal open key-
slot, said barrel having a portion at its lower
end journaled in said bridge-member, means 55
at the upper end of said push-member to re-
tain said barrel against longitudinal displace-
ment from said bore, said barrel having a re-
duced portion providing an annular space
between the same and the walls of said bore, 60
and a stop-pin fixed in said push-member to
project into said annular space in predeter-
mined position to match a selectively located
clearance notch of a proper key inserted in
said barrel. 65

In testimony, that I claim the invention set
forth above I have hereunto set my hand
this 18th day of March, 1925.

FRANK T. STUART.
